METHOD AND APPARATUS FOR PREVENTING COIL BREAKS IN SHEET METAL

Ambrose J. Wardle and Harvey D. Miller, Youngstown, Ohio, assignors to The McKay Machine Company, Youngstown, Ohio, a corporation of Ohio

Application June 26, 1934, Serial No. 732,544

16 Claims. (Cl. 153—54)

This invention relates to a method and apparatus for preventing coil breaks in strip sheet metal, and is a continuation in part of our application Serial No. 507,506, filed January 8, 1931.

It is the present practice to coil so-called "strip" sheet metal as it passes from the hot rolls, and the successive coils are taken from the rolls and permitted to cool. The gradual cooling of the coils causes the metal to become annealed to a certain extent, and when the metal is subsequently uncoiled when cool, sharp breaks or kinks occur in the metal, such breaks being known in the trade as "coil breaks". The uncoiling or unwinding of the coils usually is accomplished merely by loosely arranging the coil in an enclosure commonly termed a "coil box", and pulling the free end of the strip. The metal, as it progressively unwinds, tends to retain its curved shape due to the fact that the metal "sets" or assumes the curved shape of the coil when cooling, and the pulling of the free end of the strip from the coil causes the coil breaks referred to.

The occurrence of coil breaks in strip sheet metal is of quite serious consequence for several reasons. In the first place, the coil breaks cannot be completely removed from the metal by any known method, and the subsequent forming of metal articles, as for example, by stamping or die-drawing, causes the imperfections of the coil break to become apparent in the surfaces of the metal. It is well known that these surface imperfections cannot be completely covered by surface coating compositions, and thus the value of the metal is materially reduced. For example, strip material containing coil breaks cannot be satisfactorily employed for cold rolling in the manufacture of automobile body sheets or of the highly finished die-drawing sheets.

Moreover, because of the economy in manufacture effected by coiling sheet metal, it is desirable that its use be extended to wider sheets of metal than are usually included in the term "strip" metal. The extension of the coiling practice to wider sheets has been limited, however, due to the difficulties experienced with the coil breaks referred to and the impossibility of using sheets in which coil breaks occur in connection with particular classes of work.

Numerous methods have been proposed for removing coil breaks, and these methods, so far as we are aware have been only partially successful. The coil breaks occurring in the strip metal can be apparently eradicated by some of the methods now in use, but they again develop to mar the surface of a sheet after it has been subjected to such processes as die-drawing. In this connection it will be noted that these methods now in use have been referred to as methods for removing coil breaks, and so far as we

are aware, no method ever has been devised whereby the creation of the coil breaks has been prevented.

An important object of the present invention is to provide a method of uncoiling sheet metal to prevent the creation of coil breaks, thus eliminating the necessity for attempting to remove the coil breaks, and rendering the strip suitable for use for making sheets and other articles which cannot now be satisfactorily made because of the presence of the coil breaks.

A further object is to provide a method of uncoiling sheet metal so as to provide a flat sheet of metal without any coil breaks therein, thus making it practicable to extend the practice of coiling metal strip to relatively wide sheets.

A further object is to provide a method of uncoiling sheet metal by resisting the uncoiling of the metal and at the same time causing it to "break" around a reverse curve starting from the point at which the sheet leaves the coil to prevent the formation of coil breaks in the metal.

A further object is to provide a method of the character outlined wherein a pulling force is exerted upon the sheet as it is uncoiled while the uncoiling action is resisted by a metal working member about which the sheet is caused to take a reverse "break" starting from the point at which the sheet leaves the coil to thus prevent the formation of coil breaks in the sheet as it is uncoiled.

A further object is to provide an apparatus for uncoiling sheet metal which results in the taking off of the sheet in substantially flat form without the presence of coil breaks therein.

A further object is to provide a novel form of apparatus wherein the placing of a coil of sheet metal in operative position in the apparatus is facilitated, and wherein the sheet, as it is uncoiled, passes from the apparatus without the presence of coil breaks therein.

A further object is to provide an apparatus of the character referred to wherein a sheet working member is maintained in engagement with the coil and is caused to exert a pressure thereagainst to resist the uncoiling of the strip, and to provide pulling means for uncoiling the strip at such an angle with respect to the sheet working member as to cause the sheet to "break" around the sheet working member in uniform contact therewith, due to the resistance to the uncoiling of the strip, thus preventing the formation of coil breaks in the strip as it is uncoiled.

Other objects and advantages of the invention will become apparent during the course of the following description.

In the uncoiling of strip metal it is the common practice to support a coil on cradle rolls and to uncoil the metal by pulling the outer end of the strip from the coil without resisting the turning

movement of the coil. Under such conditions, the strip, after it leaves the coil, tends to maintain the curvature of the coil, and the pulling force exerted in uncoiling the strip causes the 5 well known "breaks" to occur at spaced intervals along the strip. It is this fault which has proved a serious difficulty in extending the use of coiled strip metal. We have found that if the turning movement of the coil is resisted as the strip is 10 uncoiled therefrom, the same tendency of the strip to maintain the curvature of the coil is present, but the "breaks" occur progressively closer as the resistance to the turning movement of the coil is increased. However, it has 15 been found that the breaks cannot be wholly eliminated merely by increasing the resistance to the turning movement of the coil, it being possible merely to cause the breaks to occur in close parallel lines, in which case the individual 20 breaks are reduced so far as the grain structure of the metal is concerned without the elimination of the breaks.

We have further discovered that a sheet working member, such as a pinch roll, can be arranged against the surface of the coil and the free end of the strip pulled from the coil in such a manner as to cause the strip to tend to take a reverse curvature around the metal working member. With such a method, the strip as 25 it is uncoiled is not permitted to follow its tendency to retain the curvature of the coil, but is caused to tend to assume a reverse curvature starting from the point at which the strip leaves the coil. This method of uncoiling strip metal 30 is highly advantageous provided the turning movement of the coil is substantially resisted to cause the strip to follow the curvature of the sheet working member or pressure roll.

In this connection, attention is invited to the 35 fact that if a method such as that outlined is employed without substantial resistance to the turning movement of the coil, the strip as it is uncoiled will tend to follow the curvature of the pressure roll but not to a sufficient extent 40 to cause the grain structure of the strip to be uniformly worked. In other words, the result of such action is to cause the breaking of the sheet along parallel lines which move progressively closer together as the resistance to the turning 45 movement of the coil is increased. A substantially different and vitally important result can be obtained, however, as compared with the practice of merely resisting the turning movement of the coil without the use of the metal working 50 member. In the latter case, the parallel lines along which the metal breaks can be brought progressively closer together as the resistance to the turning movement of the coil is increased, but a uniformity in the working of the sheet 55 cannot be obtained, and as stated above, the best results which can be obtained by such method is the increasing of the number of breaks and the decreasing of the degree of the individual 60 breaks.

The vital difference referred to lies in the 65 fact that when a metal working member of the character referred to is employed, the increasing of the resistance to the turning movement of the coil brings the lines in the coil break 70 progressively closer together until the resistance to the turning movement reaches such point as to cause the strip to "hug" the surface of the metal working member. At such point, the individual lines of coil break in the sheet will 75 wholly disappear and a condition will be obtained

wherein the grain structure of the sheet is uniformly worked, thus greatly increasing the plasticity of the sheet and eliminating coil breaks therefrom.

We have also discovered that while any suitable 5 means may be employed for resisting the turning movement of the coil, the most advantageous method lies in the exertion of pressure against the coil by the metal working member employed. Accordingly the present method contemplates the 10 use of a metal working member in the form of a pinch roll about which the metal assumes a reverse curvature as it leaves the coil, while simultaneously resisting the turning movement of the coil preferably by exerting a pressure against the 15 pinch roll to maintain it under pressure against the coil and thus grip the convolutions of the coil between the pinch roll and the mandrel, to resist the turning movement of the coil. This method of procedure, of course, can be varied, 20 for example, by adding an adjustable brake to the pinch roll to variably resist the turning movement thereof.

The extent to which the strip is "broken" 25 around the pinch roll is not critical, but it is preferred that it be carried out to a substantial extent. For example, in practice, we have found that highly advantageous results are obtained by "breaking" the strip around the pinch roll to an extent as close to 90 degrees as possible, although 30 even better results can be obtained if the strip is carried around the pinch roll 180 degrees. The latter operation offers substantial difficulties from a practical standpoint, and it is preferred that the strip be carried around the pinch roll to an 35 extent approximating from 80 to 90 degrees because of the advantageous results obtained by such method in conjunction with the elimination of operating difficulties. We have also found this result advantageous for the reason that it carries 40 the sheet as it leaves the coil substantially away from a plane of tangency with the coil and thus reduces the transmission of a direct uncoiling movement to the coil as the sheet is pulled therefrom and renders the pressure of the pressure 45 roll against the coil more effective in resisting the turning movement of the latter.

From the foregoing, it will be apparent that 50 instead of the usual practice of attempting to remove coil breaks from the strip after their formation therein, the present method contemplates the prevention of the formation of coil breaks as the sheet is unwound from the coil. In the subsequent processing of the metal, therefore, as in the case of die-drawing, cold rolling 55 or the like, the development of surface or structural imperfections due to incompletely removed coil breaks is wholly prevented.

In the drawings we have shown one form of 60 apparatus particularly adapted for practicing the method. In this showing:

Figure 1 is a transverse central vertical sectional view through the apparatus.

Figure 2 is a front elevation, parts being shown 65 in section;

Figure 3 is a section on line 3-3 of Figure 2, the arbor being shown in retracted position, and,

Figure 4 is a detail elevation of one of the 70 brake devices.

Referring to the drawings, the numeral 70 designates a pair of side frames as a whole, and the forward end of each side frame extends upwardly as at 11 to form a standard. Each standard 11 is provided with a vertical slot 12 flanged as at 13 to form a guideway. A cross-head 14 75

extends between the side frames 10 and has its ends projecting into the guideways 13 as shown in Figure 2. Bearing blocks 15 are carried by the ends of the cross-head 14 and are slidable in the guideways 13.

Each block 15 carries a bearing 16 rotatably supporting the trunnions 17 of a back-up roller 18. A vertical shaft 19 is connected at its lower end to the cross-head 14 and is provided at its upper end with a piston 20 reciprocating in a cylinder 21. This cylinder is flanged at its lower end as at 22 and bolted as at 23 to a support 24 mounted upon the upper ends of the standards 10 and extending therebetween.

Below the back-up roller 18, a metal working member 25 is arranged, and this member is in the form of a pressure roller. The ends of the roller 25 are mounted in bearings 26 slidable in the guideways 12. The ends of the roller 25 project beyond the side frame members and are provided at their ends with brake drums 27 surrounded and engageable by a split brake band 28. The free ends of each brake band extend upwardly and are arranged on opposite sides of a lug 29 carried by each end of the crosshead 14. A spring 30 urges the ends of each brake band away from each other, and a bolt 31 is adapted to tighten each of the brake bands, as will be apparent. The brake devices may be of any other desired type and provide means for adjustably resisting the turning movement of the metal working roller 25.

A pair of spaced supports 32 are secured against the outer face of one of the side frames 10 and extend transversely therefrom. A plurality of supporting rollers 33 are journaled between the supports 32 and have curved supporting surfaces as shown in Figure 3. These supporting surfaces are adapted to engage a cylindrical arbor 34 which is reciprocable transversely with respect to the side frames 10. A bearing 35 is mounted in each side frame to slidably and rotatably receive the arbor 34, and a substantially conical head 36 is carried by the free end of the arbor to facilitate its entrance into the bearing 35 at the side of the apparatus opposite the supporting rollers 33. The arbor 34, while described as a single element, is preferably made up of a series of rollers 34' arranged in end to end relation, to permit a coil to shift itself more readily on the arbor to compensate for distortion of the coil, as will become apparent.

The rollers 34' of the arbor 34 are supported by ball or roller bearings 37 in which is mounted a cylinder 38. The bearings 37 permit the arbor to rotate about the cylinder 38 while the bearings and their cages prevent relative longitudinal movement between these elements. The cylinder 38 is provided with a laterally extending finger 39 slidable in a guide slot 40 formed in a guide rail 41 secured to the top of one of the supports 32. A hollow piston rod 42 is secured at its outer end to a bracket 43 connected between and extending above the supports 32. The piston rod 42 is arranged in axial alignment with the cylinder 38 and extends therewith through a stuffing box 44. The piston rod 42 communicates with the interior of the cylinder and is provided at its inner end with a piston 45 reciprocable in the cylinder.

Air for the operation of the cylinders 21 and 38 and associated elements is derived from any suitable source of pressure. In Figure 2, a pipe 46 is illustrated as being connected at one end to a conventional reducing valve 47, while the oppo-

site end of the pipe 46 is adapted to be connected to the source of air pressure. The reducing valve is employed in order that a desired predetermined pressure may be supplied to the cylinder 21. From the reducing valve, the pipe 48 leads to a manually operable control valve 49, and branch pipes 50 lead from the control valve to the ends of the cylinder 21 in order that air pressure may be introduced into either end of the cylinder and exhausted from the opposite end. Air pressure is similarly utilized for operating the cylinder 38. The reducing valve 47, or a similar valve, may be employed for supplying air to the cylinder 38, and a manually controlled valve (not shown) controls the supply of fluid pressure from the reducing valve, or from the source of pressure to a pair of pipes 51 and 52. The pipe 51 communicates with the outer end of the piston rod 42 to supply fluid pressure to the outer end of the cylinder 38. The pipe 52 is in the form of a flexible hose to permit reciprocation of the cylinder 38 to take place. The cylinder, however, is prevented from rotating during its reciprocation by the arrangement of the finger 39 in the guide slot 40.

Means are provided for placing a coil of strip or sheet metal in position in the apparatus. A plate 53 is arranged between the side plates 10 near the bottom thereof, and a shaft 54 extends between the side plates to pivotally connect the plate 53 thereto. The plate 53 is provided with an arcuate depression 55 to receive a coil 56 of strip or sheet metal. An adjusting member 57 having an arcuate inner face is arranged over the plate 53, as shown in Figure 1. A screw 58 is connected to the adjusting member and passes through a lug 59 carried by the plate 53. The member 57 is adjustable forwardly to assist in steadyng the coil 56 on the plate 53 and to properly position the coil. The cross-head 14 is provided near opposite ends thereof with outstanding lugs 60 in which are arranged vertical rods 61. These rods are connected at their lower ends to links 62, as at 63, and the lower ends of the links 62 are pivotally connected as at 64 to opposite sides of the plate 53. Accordingly it will be apparent that vertical movement of the cross-head 14 will be transmitted to the plate 53 to raise and lower the latter.

Rearwardly of the standard 11, each side frame is provided with a vertical guide slot 70 in which are arranged upper and lower sets of bearings 71 and 72. The upper bearing 71 rotatably supports rollers 73, while a similar set of lower rollers 74 is journaled in the bearing 72. One of the sets of rollers referred to is positively driven by any suitable source of power to withdraw the sheet from the coil, and the sheet passes between the rollers 73 and 74 in the manner shown in Figure 1.

Screws 76 are adapted to adjust the height of the lower rollers 74. These screws are threaded in the lower bearing blocks 72 and carry worm gears 77 at their lower ends meshing with worms 78 carried by shafts 79. These shafts and the shafts of the screws 76 are journaled in bearing members 80.

A threaded stem 81 is arranged over each bearing block 71 and is adapted to be fed upwardly and downwardly by a worm wheel 82 meshing with a worm 83 carried by a shaft 84. The stems 81 pass through plates 85 at the top of the guide slot 70, and are provided at their lower ends with washers 86 contacting with the upper ends of springs 87. The lower ends of these springs bear against the bearing blocks 71 to exert a downward pressure thereagainst.

After passing from the pinch rolls 73 and 74, the sheet passes between upper and lower sets of leveling rolls 89 and 90. These rolls are adapted to bend the sheet back and forth during its passage therebetween, similar to the action of the usual roller leveler, and the sheet passes from the apparatus substantially flat. The upper rolls 89 are journalled in a bearing block 91, and the lower rolls in a somewhat similar block 92.

The bearing blocks 91 are stationary and each is provided in its ends with vertically extending shafts 93 connected to worm wheels 94. These worm wheels mesh with worms 95 carried by shafts 96, and accordingly rotation of the shafts 96 is adapted to rotate the shafts 93. The lower ends of the latter shafts are threaded as at 97 in bosses 98 carried by the lower bearing block 92, and accordingly it will be apparent that rotation of the shafts 93 is adapted to transmit vertical movement to the bearing block 92. Springs 99 have their upper ends seating against the bottom of the block 91 and their lower ends against the bottom of recesses 100 formed in the lower bearing block 92.

In actual practice, the coils of strip metal are piled one upon another while hot, and the result is that many of the coils are distorted from their normal shapes. For example, one end of the coil may be substantially circular and the other end elliptical, and it is necessary for the apparatus of the present invention to take care of coils of distorted shapes. For this purpose, a pair of guides 101 is supported by the side frame members 10 beneath the arbor 34, as shown in Figures 1 and 2. The guides 101 fit substantially close to the arbor and for this purpose are cut away as at 102. When the apparatus is in operation, the length of the coil is slightly less than the distance between the guides 101, and the guides prevent the coils from creeping longitudinally with respect to the arbor, and thus assist in providing a straight flat finished sheet.

The operation of the apparatus is as follows:

The arbor 34 is normally in retracted position, thus leaving clear the space between the lower portions of the side frames 10 to permit the coil to be moved to operative position. The plate 53 is normally arranged in the lower position shown in Figure 1, and accordingly is in a position to receive one of the coils 56. As soon as the coil is arranged in proper position in the depression 55, the control valve 49 is operated to admit fluid pressure into the bottom of the cylinder 21. The piston 20 accordingly will be moved upwardly, together with the piston rod 18, cross-head 14, lugs 60, roller 25, and the plate 53 through its connections with the lugs 60. Thus the coil 56 will be moved upwardly to the operative position illustrated in Figure 1.

At this point fluid pressure is admitted into the piston rod 42 through the pipe 51, thus building up a pressure in the outer end of the cylinder 38 whereby it will be apparent that this cylinder will be moved outwardly together with the arbor 34. This action is continued until the arbor reaches the operative position shown in Figure 2, at which time it will be rotatably supported by both bearings 35. At this point, fluid pressure is cut off from the bottom of the cylinder 21 and admitted to the top thereof to move the piston 20 downwardly, together with the elements connected thereto. Accordingly it will be apparent that the plate 53 will be returned to lower position, while the rollers 18 and 25 will be moved down-

wardly, the latter being brought into engagement with the coil 56.

It will be apparent that the reducing valve 47 will supply any desired fluid pressure to the cylinder 21, and that the pressure of the roll 25 against the coil will be directly dependent upon the degree of fluid pressure. In this connection attention is invited to the fact that the roller 25 is preferably arranged with its axis in the vertical plane of the axis of the arbor 34.

The free end of the sheet from the coil is introduced between the first pair of pinch rolls 73 and 74, and since these rolls are positively driven, the sheet will be withdrawn from the coil and the coil will be progressively unwound. The unwinding of the coil obviously revolves the arbor 34, the bearings 37 permitting this revolving action to take place. During this action, however, the cylinder 38 will be held against revolving by the arrangement of the finger 39 in the guide slot 20

The sheet also passes between the second pair of rolls 73 and 74 and accordingly these rolls also act as pinch rolls gripping the sheet to unwind the coil. From the pinch rolls, the sheet passes between the leveling rolls 89 and 90 and is discharged therefrom in substantially flat form. As previously stated, the present invention does not operate to remove coil breaks from the sheet, but on the contrary it definitely prevents the formation of coil breaks. If the roll 25 is merely brought into contact with the outer face of the coil and the pinch rolls 73 and 74 operate to unwind the coil, the resistance to the turning movement of the coil will be substantially negligible and the result will be that the sheet will not be tensioned as it is unwound and will not closely follow the curvature of the roll 25. Such operation of the apparatus will not effectually prevent the formation of coil breaks.

It has been found however that if the turning movement of the coil is resisted to a sufficient extent, the pinch rolls subject the sheet to a substantial tension outwardly from the point where the sheet leaves the coil, and the sheet, as it is progressively unwound, is held under such tension and is forced to "hug" the surface of the roll 25 to accurately follow the curvature thereof. In actual practice, this action causes a perfectly uniform cold working of the sheet around the metal working roll 25, and the formation of the coil breaks is prevented at their usual source.

The resistance to the turning movement of the coil may be accomplished in any desired manner. For example, the brakes 28 may offer frictional resistance to the turning movement of the roll 25, thus tensioning the sheet for the purpose stated. It is preferred, however, that all or substantially all of the resistance to the turning movement of the coil be effected by holding the roll 25 against the coil under pressure. This is accomplished in the present apparatus by means of the fluid operated piston 20 and associated parts. In this connection, attention is invited to the fact that the surfaces of the sheet are not perfect as in the case of machined metal surfaces, and the successive convolutions of the coil are subject to compression to some extent. The holding of the roll 25 against the coil under substantial pressure causes the roll to slightly embed itself into the coil, and the pulling of the sheet is accomplished only against substantial resistance since the embedding of the roll 25 must move progressively around the coil.

In other words, it is necessary for the pres-

sure of the roll 25 to compress successive portions of the coil as the strip is progressively unwound, and the resistance to the turning movement of the coil thus generated has been found particularly effective for forcing the progressively unwound strip to snugly follow the curvature of the metal working roll 25, thus effecting a perfectly uniform progressive working of the grain structure of the sheet. In setting the pressure 10 at which the roll 25 is maintained in engagement with the coil, it merely is necessary to progressively increase the pressure in the upper end of the cylinder 21 until the sheet snugly engages the surface of the roll 25. Slightly less pressure 15 may be employed, if desired, in which case added resistance to the turning movement of the coil may be provided through such means as the brakes 28. The reverse breaking of the sheet around the roll 25 obviously tends to cause the sheet to maintain its reverse curvature, but this fact is of no importance. Whereas the strip tends to maintain the curvature of the coil for the reason that it has become partially annealed and set in such shape, the cold working of the 20 sheet around the roll 25 increases the plasticity of the sheet, thus permitting it to readily flex around the first of the lower pinch rolls 14. During such period however the sheet is maintained under tension and cannot kink or break, although 25 there is substantially negligible tendency for this to occur in view of the cold working of the sheet.

As previously stated, close to the ideal operation of the apparatus for practicing the method would involve the carrying of the sheet 180° 30 around the roll 25, but an apparatus for this purpose has been found to involve substantial practical difficulties. Accordingly the present apparatus has been devised and it has been found that highly advantageous results can be obtained 35 by causing the sheet to pass around approximately 80° of the roll 25. Ordinarily, it is unnecessary to add to the resistance to the turning movement of the coil by the use of the brakes 28, but with sheets of certain types this is advisable since 40 relatively high pressures of the roll 25 against the coil are necessary when the sheet passes substantially 80° around the roll 25. It is wholly practicable to reduce the arc through which the sheet contacts with the roll 25, but greater additional 45 breaking of the coil is necessary as the degree of curvature of the sheet around the roll 25 is reduced. For practical purposes, the arc of curvature disclosed in Figure 1 of the drawings is highly satisfactory.

50 The pinch rolls 13 and 14 are preferably arranged in the respective positions shown in Figure 1, but they may be raised or lowered slightly by proper operation of the shafts 79 and 84. The pinching action between the rolls 13 and 14 is 55 accomplished through the medium of the springs 81, and the tension of these springs readily may be varied by operation of the shafts 84. Thus it will be apparent that a proper grip on the sheet 60 may be provided to enable the sheet to be unwound against the resistance offered to the turning movement of the coil 56. After leaving the pinch rolls, the strip or sheet travels to the leveling rolls where it is successively and progressively flexed back and forth, and in accordance with 65 the usual operation of a roller leveler the sheet 70 is delivered from the apparatus perfectly flat and smooth.

75 After the coil has been completely unwound, air is admitted into the cylinder 38 through pipe 52, and thus the arbor will be retracted to nor-

mal position wholly outwardly of the adjacent side frame 10. Another coil is then rolled into position on the plate 53, whereupon the valve 49 is operated to admit air into the lower end of the cylinder 21 and exhausted from the upper end thereof. The coil thus will be elevated to its proper position while the rolls 18 and 25 will be elevated above operative position. The cylinder 38 is then again moved to operative position to support the coil on the arbor, and the apparatus 10 is again in position for operation upon the downward movement of the piston 20 and roll 25.

From the foregoing it will be apparent that the present invention is clearly distinguished from prior attempts to remove coil breaks from metal strip in that it prevents the formation of the coil breaks instead of merely attempting more or less unsuccessfully to remove them. Accordingly the resultant sheet is adapted for use in high class work, such as the formation of automobile body panels, and the advantages of winding strip sheet metal in coils accordingly may be extended to sheets of any width. The invention thus results in great economy in the manufacture of sheet metal for various purposes.

It will be apparent that the present method is concerned primarily with the pulling of the strip or sheet from the coil around a metal working member of curved shape, while resisting the turning movement of the coil at least sufficiently 30 to cause the sheet to snugly follow the curvature of the metal working member as the strip is unwound from the coil. The mere tensioning of the sheet is not sufficient to substantially prevent the formation of coil breaks, but the forcing of the sheet to follow the curvature of the metal working member uniformly cold works the sheet, thus increasing its plasticity and preventing the formation of coil breaks. The method further 35 contemplates the resistance to the turning movement of the coil by the pressure of the metal working member, it having been found that the pressure of the metal working member against the coil will offer the desired resistance to the turning movement of the coil for the purpose 40 stated. The practice of the method results in the reduction of a finished sheet of surprisingly uniform surface and grain structure throughout its length, which may be subjected to any 45 of the usual forms of processing without the development of strains in the metal, which always 50 results from coil breaks.

It has been found that greatly improved results are obtained with strip steel cold rolled after having been treated in accordance with 55 the present method. Such improvement is the result of the complete uniform kneading of the metal to a high degree of cold plasticity, free from intermittent cross breaks that partially rupture the metal at intervals where the strip is 60 permitted to kink in the regular practice of uncoiling. Where the kinks occur, the metal has been greatly overworked and the further cold working of the metal such as by roller leveling, 65 recoiling or any other known process, will not correct the damage caused by coil breaks, although some improvement is noted when the metal is treated in accordance with certain prior methods and apparatus. The intervening metal between the cross breaks cannot be worked to 70 an extent that will approximate the overworking of the metal at the line of the cross breaks to provide a uniform surface structure and the results of the rupturing of the metal at the cross 75 breaks can be only partially overcome. The

effect of the cross breaks thus is apparent on the finished sheet after cold rolling. The present method and apparatus instead of attempting merely to correct the damage after it has been caused, as is done with prior methods, prevents the occurrence of the damage to the grain structure, and accordingly provides finished sheets of much higher quality and uniformity than can be obtained with any prior methods of which we are aware.

As previously stated, the resistance to the turning movement of the coil is most advantageously provided by clamping the convolutions of the coil between the metal working roll 25 and the arbor 34. In the first place, greater uniformity in the resistance to the turning movement can be obtained, and the pressure between the elements tends to embed the roll 25 in the coil due to the tight compressing of the convolutions of the coil against each other, and a better metal working action is thus provided. Of course, the pressure employed in the upper end of the cylinder 21 will depend upon the gage of the metal being worked and the width of the strip material wound on the coils. The greater the thickness of the metal and/or the greater the width thereof, the more pressure will be employed to secure the desired results.

It is to be understood that the form of the invention and the method herein described are to be taken as preferred examples of the same and that various changes in the practice of the method and in the size, shape and arrangement of parts may be made without departing from the spirit of the invention or the scope of the subjoined claims.

We claim:

1. The method of uncoiling hot rolled sheet metal to prevent the formation of coil breaks therein which comprises maintaining a cylindrical metal working member in engagement with the coil in a position parallel to the axis thereof, transmitting a pull to the free end of the sheet to cause it to pass around a substantial arc of the metal working member, and simultaneously resisting the turning movement of the coil at least to a sufficient extent to cause the sheet to snugly follow the curvature of the metal working member, whereby the metal of the sheet is worked to impart thereto a substantial degree of plasticity.

2. The method of uncoiling hot rolled sheet metal to prevent the formation of coil breaks therein which comprises arranging a cylindrical metal working member in engagement with the coil in a position parallel to the axis thereof, transmitting a pull to the free end of the sheet to cause it to pass around an arc of at least 80 degrees of the metal working member, and simultaneously maintaining the metal working member under pressure against the coil to resist the turning movement thereof to a sufficient extent to cause the sheet to snugly follow the curvature of the metal working member through its arc of contact therewith, whereby the metal of the sheet is worked to impart thereto a substantial degree of plasticity.

3. The method of uncoiling hot rolled sheet metal to prevent the formation of coil breaks therein which comprises clamping the convolutions of the coil between a mandrel and a transversely curved metal working member, and uncoiling the sheet by exerting a pull on the sheet in a plane at a substantial angle with respect to a plane tangent to the coil at the line of contact of

the metal working member therewith to cause the sheet as it leaves the coil to pass around a substantial arc of said metal working member in snug contact therewith, whereby the metal of the sheet is worked to impart thereto a substantial degree of plasticity.

4. The method of uncoiling hot rolled sheet metal to prevent the formation of coil breaks therein which comprises supporting the coil on a mandrel, maintaining a transversely curved metal working element in engagement with the coil outwardly thereof, uncoiling the sheet by transmitting a pull to the free end of the sheet in a plane at a substantial angle to a plane tangent to the coil at the line of contact of the metal working member therewith, and resisting the rotation of the coil at least to a sufficient extent to cause the sheet as it is progressively unwound to snugly follow the curvature of the metal working element by exerting a relative clamping pressure of the mandrel and metal working element against the convolutions of the coil, whereby the metal of the sheet is worked to impart thereto a substantial degree of plasticity.

5. Apparatus of the character described comprising means for rotatably supporting a coil of hot rolled sheet metal, a transversely curved metal working member engageable against the coil along the line at which the sheet leaves the coil, means for transmitting a pull to the free end of the sheet at such an angle as to cause the latter to pass around a substantial arc of said metal working member, and means for resisting the turning movement of the coil at least to a sufficient extent to cause the sheet to snugly follow the curvature of the metal working member through its arc of contact therewith, whereby the metal of the sheet is worked to impart thereto a substantial degree of plasticity.

6. Apparatus of the character described comprising an arbor for rotatably supporting a coil of hot rolled sheet metal, a transversely curved metal working member engageable against the coil along the line at which the sheet leaves the coil, means for transmitting a pull to the free end of the sheet at such an angle as to cause the sheet to pass around a substantial arc of said metal working member, and means for effecting a clamping action between said metal working member and said arbor to resist the turning movement of the coil to cause the sheet to snugly follow the curvature of said metal working member throughout its arc of contact therewith, whereby the metal of the sheet is worked to impart thereto a substantial degree of plasticity.

7. Apparatus of the character described comprising an arbor for supporting a coil of hot rolled sheet metal for rotation, a pair of pinch rolls arranged parallel to the axis of the coil and adapted to engage the free end of the sheet to unwind it from the coil, a transversely curved metal working member engageable against the coil at the line at which the sheet leaves the coil, and means for resisting the turning movement of the coil to a sufficient extent to cause the sheet to snugly follow the curvature of said metal working member as the sheet is progressively unwound from the coil, said pressure roll and said pinch rolls being so arranged with respect to each other as to cause the sheet to pass around a substantial arc of the metal working member, whereby the metal of the sheet is worked to impart thereto a substantial degree of plasticity.

8. Apparatus of the character described comprising an arbor for supporting a coil of hot rolled

sheet metal for rotation, a pair of pinch rolls adapted to engage the free end of the sheet to unwind it from the coil, a pressure roll engageable against the coil at the line at which the sheet 5 leaves the coil, said pinch rolls being offset from the plane of tangency of the sheet at the line at which it leaves the coil to cause the sheet to pass around a portion of the surface of said pressure roll, means for clamping the convolutions 10 of the coil between said arbor and said pressure roll at a predetermined pressure, and adjustable brake means for resisting the turning movement of said pressure roll to cause the sheet to be subjected to a substantial longitudinal tension be- 15 tween said pressure roll and said pinch rolls.

9. Apparatus of the character described comprising longitudinally movable means for supporting a coil of hot rolled sheet metal for rotation, means for effecting longitudinal movement of 20 said last named means from inoperative to operative position, means for elevating a coil to and supporting it in operative position to be engaged by said first named means, a pair of pinch rolls adapted to engage the free end of the sheet to 25 unwind it from the coil, and means for resisting the turning movement of the coil to subject the sheet to a substantial longitudinal tension as it is unwound from the coil.

10. Apparatus of the character described comprising an arbor adapted to assume an operative position within a coil of hot rolled sheet metal to support the latter for unwinding, said arbor being axially movable to inoperative position, power means for effecting movement of said arbor be- 30 tween operative and inoperative positions, means for elevating the coil to and supporting it in operative position to be engaged by said arbor when the latter is moved to operative position, means for engaging the free end of the sheet to unwind 35 it from the coil, and a pressure member engageable against the coil to resist turning movement thereof while being unwound.

11. Apparatus constructed in accordance with claim 10 wherein said pressure member engages 45 against the coil along the line at which the sheet leaves the coil, the means for unwinding the sheet being arranged to pull the free end thereof in a plane arranged at an angle to a tangent to the coil at the point of contact of said pressure member whereby the sheet is caused to pass partially 50 around said pressure member in a path curved opposite to the curvature of the convolutions of the coil.

12. Apparatus of the character described comprising an arbor, means for supporting said arbor for axial movement between operative and inoperative positions, means for elevating a coil of hot rolled sheet metal to and supporting it in operative position to be engaged by said arbor when the latter is moved to operative position, a pair of 55 pinch rolls arranged parallel to said arbor and engageable with the free end of the sheet to unwind it from the coil, and a pressure roll movable into engagement with the coil to clamp the latter under pressure between said arbor and said pressure roll, said pressure roll being arranged to contact with the coil along the line at which the sheet leaves the coil, said pinch rolls being offset 60 from a plane tangent to the coil at the point of contact of said pressure roll therewith whereby the free end of the sheet is caused to travel partially around said pressure roll in a curve opposite to the curvature of the convolutions of the coil, means for supporting said pressure roll for move- 65 ment in a plane coincident with the axis of the

coil, and fluid pressure means for causing said pressure roll to remain in contact with the coil under substantial uniform pressure as the coil unwinds.

13. Apparatus of the character described comprising a support including a pair of spaced side frames, alined bearings carried by said side frames, an arbor rotatable in said bearings and axially slidale from an operative position within said frames to an inoperative position to one 10 side of said support, said arbor when in operative position being adapted to support a coil of hot rolled sheet metal for rotation, a pair of pinch rolls arranged to one side of said arbor and parallel thereto, said pinch rolls being adapted to engage the free end of the sheet to unwind it from the coil, a pressure roll engageable against the coil along the line at which the sheet leaves the coil, and means for resisting turning movement 15 of said pressure roll. 20

14. Apparatus of the character described comprising a horizontal rotatable arbor adapted to support a coil of hot rolled sheet metal, a pair of pinch rolls mounted above and to one side of said arbor and parallel thereto, said pinch rolls 25 being adapted to engage the free end of the sheet to unwind it from the coil, a pressure roll engageable against the top of the coil, said pressure roll having its axis arranged substantially in the vertical plane of the axis of said arbor and contacting with the coil along the line at which the sheet leaves the coil, the horizontal plane through the line of contact of the pinch rolls with the sheet lying above the horizontal plane of the line of contact of said pressure roll and the coil, and a second pair of pinch rolls lying adjacent and parallel to said first pair of pinch rolls and positioned with respect thereto to cause the portion of the sheet passing between the two pairs of pinch rolls to travel in a plane at an angle to the plane 30 of the portion of the sheet traveling between the coil and the first named pair of pinch rolls whereby the sheet is caused to travel partially around the lower pinch roll of the first named pair. 35

15. Apparatus of the character described comprising an arbor for supporting a coil of hot rolled sheet metal for rotation, a pair of pinch rolls adapted to engage the free end of the sheet to unwind it from the coil, a pressure roll engageable against the coil at the line at which the sheet leaves the coil, and means for maintaining 50 said pressure roll against the coil and the coil against said arbor at a predetermined pressure to resist the turning movement of said coil as the 55 sheet is uncoiled, said pressure roll and said pinch rolls being so arranged with respect to each other as to cause the sheet as it is unwound from the coil to pass around a substantial arc of said pressure roll. 60

16. Apparatus of the character described comprising an arbor for supporting a coil of hot rolled sheet metal for rotation, a pair of pinch rolls adapted to engage the free end of the sheet to unwind it from the coil, a pressure roll engageable against the coil at the line at which the sheet leaves the coil, said pinch rolls being offset from the plane of tangency of the sheet at the line at which it leaves the coil to cause the sheet to pass around a portion of the surface of said 70 pressure roll, and means for clamping the convolutions of the coil between said arbor and said pressure roll. 75
